UNITED STATES PATENT OFFICE.

THOMAS LEONARD McMINN, OF WELLINGTON, ALABAMA, ASSIGNOR OF ONE-SIXTH TO H. M. BURGESS, ONE-TWELFTH TO ROBERT BURGESS, ONE-TWELFTH TO B. W. HARVEY, ONE-TWELFTH TO T. R. BURGESS, ONE TWENTY-FOURTH TO M. D. BURGESS, AND ONE TWENTY-FOURTH TO W. E. BURGESS, ALL OF WELLINGTON, ALABAMA.

HYDRAULIC SIPHONING MACHINE.

Application filed December 13 1923. Serial No. 680,563.

To all whom it may concern:

Be it known that I, THOMAS LEONARD McMINN, a citizen of the United States, and a resident of Wellington, in the county of 5 Calhoun and State of Alabama, have invented certain new and useful Improvements in Hydraulic Siphoning Machines, of which the following is a specification.

This invention relates to a hydraulic siphoning machine and has for its object the provision of a device which is adapted to be employed in conjunction with a siphon or other source of water supply for forcing a portion of the water to a higher level by 10 the power developed by the pressure of the source of water.

A further object of the invention is the provision of a device in which the pump is operated by a siphon for elevating the water 15 to a higher level and in which the combined action of the pump and siphon provides a constant water pressure from shallow wells and cisterns or springs.

A further object of the invention is the provision of a pump operated by the force 20 of water under pressure and which water forms the usual supply to one or more buildings, the pressure of the water being utilized in the pump for raising the water to a higher elevation than the pressure of the water 25 is ordinarily capable of raising the water, the supply of water being automatically controlled by the pressure acting on the pumping mechanism.

A still further object of the invention is the provision of a device designed to cooperate with the siphon for raising water from a great number of wells and cisterns with sufficient force to give a constant water pressure 30 for any reasonable number of feet above the surface of the ground and to supply buildings situated on elevated places in cities with sufficient water where the normal water pressure is incapable of furnishing an adequate supply to said buildings.

Another object of the invention is to supply 35 an increased water pressure in those places where it is desired to run fans, dish washing and other machines which are driven by water power and in which the pressure of the water is insufficient for the purpose.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a plan view of an embodiment 65 of my invention.

Figure 2 is a longitudinal side view of the device shown in Figure 1.

Figure 3 is a transverse vertical section of the valve box for controlling the inflow 70 of water.

Figure 4 is a transverse vertical section of the valve box and valve for controlling the outflow of water.

Figure 5 is an end view of the machine. 75

Figure 6 is a horizontal section of my hydraulic siphoning machine.

Figure 7 is a longitudinal vertical section of the machine.

Figure 8 discloses more or less diagrammatically my improved hydraulic machine used in connection with a siphon and a plurality of spigots. 80

Figure 9 shows diagrammatically a variation of my machine employed in connection 85 with a siphon.

Figure 10 shows diagrammatically the connection of my machine with the siphon.

Referring more particularly to the drawings, 1 designates the working barrel or low pressure cylinder of my hydraulic pump in which is adapted to be reciprocated a piston 2. The opposite ends of the cylinder are flanged as shown at 3 and 4 and to the flange 4 is bolted a head 5 having an internally threaded boss 6. A high pressure cylinder 7 open at its opposite ends has its inner end threaded and screwed into the internally threaded boss. The other end of the cylinder is likewise threaded and upon which is screwed an internally threaded cap 8.

A piston 9 operates in cylinder 7 and is connected to the outer end of a rod 10, the

inner end of the rod being rigidly connected with the piston 2. The rod is adapted to slide through a stuffing box comprising an externally threaded nipple 11 and a cap 12.

5 The cap is adapted to retain the usual packing upon the end of the nipple 11.

The rod 10 has a short projection 13 projecting beyond the piston 2 and threaded to receive the internally threaded end of a 10 sleeve 14. A bolt 15 is screwed into the opposite threaded end of said sleeve for supporting a hanger 16. The upper end of the hanger 16 is provided with a passage through which the bolt 15 is inserted and the 15 lower end is provided with an internally threaded passage into which is screwed the bent end 17 of a bar 18 adapted to be reciprocated upon the bottom of a cylinder 19. Said cylinder has one end closed as shown 20 at 20 and its other end open but provided with flanges adapted to be secured to the flanges 3 of the working barrel 1.

The cylinder 19 is provided with flanged 25 openings 21 and 22 formed in the side wall of the cylinder with the flanges 23 projecting laterally from said cylinder. Mounted upon one laterally projecting flange 23 is a square valve casing 24. The inner end of the square casing 24 is provided with a 30 flange 25 adapted to be secured to the outer end of the projection 23 by means of bolts 26. The side walls of the casing 24 are provided with longitudinal passages through which are inserted bolts 27 for not only 35 locking the cover 28 from the outer end of the casing but aids in supporting the casing on the lateral projection 23 when the said bolts are screwed into threaded perforations on the end of said projection.

40 The casing 24, as shown more particularly in Figure 3, is provided with an upper chamber 29 and a pair of lower chambers 30 and 31. The partition 32 which separates chamber 29 from 30 and 31 is provided 45 with a passage 33 upon which is adapted to seat a valve 34. The partition is likewise provided with an opening 35 affording communication between chamber 29 and 31 and is adapted to be closed by a valve 36 operated by an arm 37. The arm 37 and an arm 38 which carries valve 34 is integrally formed with a boss 39 mounted on and for rotation with a shaft 40.

An opening 41 formed in the top of the 55 chamber 29 is adapted to be closed by a plug 42. The opening and plug permits inspection of the interior of the casing.

An inlet pipe 43 is in communication with the chamber 29 and is connected with an 60 inlet pipe 44 which is in communication with the supply pipe of the water source.

The valve box 24 has an opening 45 which places the chamber 31 in communication with the interior of the cylinder 19 and 65 when the valve 36 is in the position shown

in Figure 3 the pressure of water from the pipe 44 is directed against the inner face of piston 2.

The valve box 24 has a second opening 46 formed at the bottom of the chamber 30 and to which is connected a pipe 47 which is directed forwardly and then upwardly and connected to a pipe 48. The forward end of the pipe is connected to a threaded boss 49 which embraces an opening 50. This opening is formed in the cylinder head 5 and places said pipe in communication with the forward end of the cylinder 1 for reversing the piston 2 when the valve 34 has been opened and valve 36 closed.

80 The exhaust valves for permitting the water to discharge from either the forward or the rear end of cylinder 1 and likewise from the cylinder 19 is included in a valve casing 51. This valve casing is similar in construction to valve casing 24 and is shown in Figure 4 as having a lower chamber 52 and two upper chambers 53 and 54.

85 As has been explained the forward end of conduit 48 is connected to the cylinder head 5 while the opposite end is extended laterally, as shown at 55 and connected with an opening 56 in the top of the chamber 53. An opening 57 in the rear wall of the casing 51 affords an open communication between the chamber 54 and the interior of the cylinder 19. A drain pipe 58 is connected with an opening in the bottom of the chamber 52 to permit the water to drain from this chamber which is alternately supplied from chambers 53 and 54.

90 A shaft 59 is mounted in an externally threaded boss 60 which forms a bearing for said shaft and a cap nut 61 is screwed onto the end of the threaded boss with the usual packing for sealing the trunnion of the shaft 59 from loss of fluid around said shaft.

95 It will be noted in referring to Figure 6 that the shaft 40 is likewise mounted centrally of the passage in the externally threaded boss 62 formed integrally with the rear wall of the valve box 24 and has a cap nut 63 screwed on its ends carrying packing to prevent loss of fluid around the shaft.

100 A hub 64 is rigidly connected to the shaft 59 and is provided with a pair of integrally formed oscillating arms 65 and 66. The arm 65 carries a valve 67 adapted to close at times a passage 68 formed in the partitions between the chamber 53 and the chamber 52. A valve 69 is carried by arm 66 and is adapted to control the flow of fluid through a passage 70 formed in the partition between the chamber 54 and chamber 52.

105 A crank shaft 71 is mounted for oscillation in the cylinder 19 and has a reduced portion at one end mounted for rotation within a socket in a boss 72 integrally

formed with the shaft 40. The opposite end of the crank shaft is provided with a reduced portion adapted to be rotatably mounted within a socket formed in a boss 5 73 which is integrally formed with shaft 59.

Upon the central portion of the shaft 71 is loosely mounted a wheel 74 which is provided with a pair of spaced pins 75 and 76 10 projecting laterally from a face of the wheel and which are adapted to engage at times a pin 77 rigidly connected to the shaft 71. A pin 78 rigidly connected to the shaft adjacent one end is adapted to be alternately engaged by pins 79 and 80 projecting 15 from one end of the boss 72. A pair of pins 81 and 82 projecting laterally from the face of the boss 73 is adapted to be alternately engaged by a pin 83 rigidly connected with shaft 71.

The shaft 71 is provided with a crank 84 which is located between the wheel 74 and the boss 73. A spring 85 has one end connected to the crank as shown at 86 and 25 its other end connected to an eye 87. The eye is screwed into a plug 88 which is threaded into the threaded opening in the closed end 20 of the cylinder 19.

A strap 89 secured at 90 to the oscillating 30 bar 18 adjacent its inner end is coiled about the periphery of the wheel 74 and secured at 91 to said wheel. A strap 92 secured to the outer end at 93 of the bar 18 has its opposite end secured at 91 to the wheel 74. 35 A pipe 94 is connected to the pipe 44 and is carried forward of the pumping machine and placed in communication with the outer end of the cylinder 7 by means of the short connection 95. A valve 96 in the pipe 40 94 permits the water from pipe 44 to flow into cylinder 7 at its forward end but prevents a return flow of the water. A pipe 97 connects the pipe 44 to the inner end 45 of the cylinder 7. A valve 98, located in the pipe 97 permits water to flow to the cylinder 7 but prevents a back pressure of the water upon the source of supply through the pipe 44.

A pipe 99 connected through the inner 50 end of the cylinder to the boss 6 is connected with a pipe 100 which forms the supply pipe for the buildings. A spigot 101 is employed for the purpose of releasing water from the pipe 100. An air chamber 102 is connected 55 to the high pressure pipe 100 and is adapted to provide elasticity for the whole machine during its operation. The chamber 102 provides an air cushion in the same manner as is ordinarily employed in force pumps. A 60 valve 103 is located in pipe 99 to permit the water to flow to pipe 100 but prevents return of water to the system through the inner end of cylinder 7.

A pipe 104 connected with the pipe 94 and 65 likewise the short connection 95 to the outer

end of the cylinder 7 is likewise connected with pipe 100 and adapted to supply said pipe with water under an increased pressure. A valve 105 located in pipe 104 prevents the return of water to the pipe 94 and 70 the forward end of cylinder 7 but permits the water under high pressure to flow through the spigot 101 when said spigot is operated.

Referring more particularly to Figure 10, 75 an adaptation of my invention to a siphon is shown. A source of supply 106 such as a cistern, well or spring is disposed below the level of the pump 1. A pipe 107 having its lower end immersed in the source is extended vertically upward and has a horizontal portion 108 and a return vertical portion 109 extended downwardly and forms the train for the siphon. The lower end is located in a pool or cistern 110 which must be located below the source 106 in order to operate the siphon.

A pipe 44 connects the vertical pipe of the siphon to the valve casing 24 of the hydraulic pump shown in Figure 1. The valve casing 51 is connected to a drain pipe 58 which is in communication with the drain pipe 109 of the siphon. The high pressure cylinder 7 is shown connected with the pump 1 and the pipe 100 is connected with 95 the high pressure cylinder 7.

Figure 8 shows how the high pressure system pipe 100 may be tapped by two or more pipes and how any number of hydrants may be arranged in connection with the pipes and this provides a means for supplying two or more families with water from the same pump. It will only be necessary, to start the flow of water, to turn the hydrant and to stop the machine would be to turn off the 100 hydrant. The pump 1 is connected to the siphon 113 while a pump 1^a is connected to a tank 115 and a higher level in the tank 114. The arrangement of the several pumps in Figure 8 discloses the connection of both 105 pumps to the drain of the siphon. The connection of the several pumps to the same drain is for the purpose of economy in the cost of installing the machine. The drain pipe in all cases where the siphon is employed must be submerged in water in order to prevent air entering the siphon and causing a drain of the pipes of said siphon and it must be remembered that in order to operate the siphon successfully and the machine in 110 connection with said siphon that the source of supply, as shown at 106, must always be located several feet above the well 110 and it further must be borne in mind that the highest point in the siphon must not be the full latitude of the source to which the atmospheric pressure of a given location will support a column of water. In other words, it must be low enough to allow the water to

115 enter pipe 44 under pressure. The shallower 120

125

130

the well the stronger the pressure will be had provided the drain pipe has sufficient fall. The pumps may be made in different sizes to meet different needs and if the quantity of water desired cannot be supplied by one pump any number of pumps 1^a and 1^b may be connected to the same system in parallel, as shown in Figure 9.

The operation of my device is as follows:

10 Referring to Figure 3, the valve 36 is shown in open position thereby permitting open communication between the source of supply through pipe 43, chamber 29, passage 35, chamber 31 and the opening 45 to 15 the interior of the cylinder 19. The pressure of the water on piston 2 forces said piston forwardly in cylinder 1 and likewise piston 9. Since the forward end of cylinder 7 is in open communication with pipe 44, 20 water under pressure from the source will fill that part of cylinder 7 and as piston 9 is moved forwardly and the faucet 101 is open the water will be forced out through connection 95, pipe 104 and through pipe 100 25 and faucet 101. As soon as the piston 2 is moved to the limit of its stroke adjacent the cylinder head 5 and during the forward movement of said piston, the oscillating bar 18 is carried forwardly rotating the wheels 30 74 in the direction indicated by the arrow in Figure 7.

The shaft 71 is rotated through pin 75 engaging pin 77 and as the crank passes dead center, spring 85 will cause the crank to 35 operate rapidly by the sudden pull of the spring on the crank and force the pin 77 on the shaft 71 into engagement with pin 76 on wheel 74. At the time that the spring 85 causes rotation of shaft 71, shaft 40 will 40 be oscillated and cause valve 36 to close passage 35 and valve 34 to open passage 33 whereby water under pressure will pass through chamber 30 to pipe 47, pipe 48 and into the forward end of cylinder 1.

45 It must be borne in mind that any water in the forward end of cylinder 1 between the piston 2 and the cylinder head 5 is forced outwardly during the forward stroke of piston 2 and through pipe 48 and into the chamber 53 in valve casing 51. This water passes by the open valve 67 into chamber 52 and out through the drain 58. When shaft 71 is rocked in the manner described, shaft 59 is rocked simultaneously with the shaft 40 50 which reverses the position of valves 34 and 36. Valve 67 is thereby closed while valve 69 is opened and these valves are operated through the operation of shaft 71 at the limit of forward movement of the piston 2 55 and likewise of the oscillating rod 18. Since valve 34 is open and water under pressure is flowing to the forward end of the cylinder 1 and acting upon piston 2, water is being released from cylinder 19 through the passage 57, passed valve 69, which is now open,

through chamber 52 and out through the drain 58. The rearward movement of piston 2 causes water pressure between the piston 2 and cylinder head 5, the rod 18 likewise moving rearwardly and causing strap 92 to rotate the wheel 74 in a direction which is opposite to the direction of rotation as shown by the arrow in Figure 7.

The pin 76 being in engagement with the pin 77 on the shaft 71, causes rotation of 75 said shaft until the crank 86 has passed the dead center when the spring 85 will suddenly complete the revolution of shaft 71 and cause pin 83 on said shaft to engage 82 about the time that the spring 85 rotates 80 shaft 71 and thereby causing rotation of shaft 59 and close valve 69 and again opening valve 67. At the same time the shaft 71 causes closing of the valve 34 and opening of valve 36 since the pin 78 engages pin 79 85 when the spring 85 causes rotation of the shaft 71 and oscillates the shaft 40 for reversing the previous position of the valves whereby the water flows from chamber 29 to chamber 31 through opening 45, filling the 90 cylinder 19 for exerting pressure on piston 2.

It will be seen that as piston 2 is moved in alternate directions the reciprocating bar 18 will likewise be moved in a similar manner for causing a reversal of the application 95 for the pairs of valves 34, 36 and 67, 69 and changing the flow of the water in the cylinders.

The force exerted on piston rod 10 is 100 equivalent to the product of the area of the piston 2 multiplied by the pressure under which the water enters the cylinder 19 through the passage 45. This force is transmitted to piston rod 30 to the piston 9 of reduced area. The force exerted on piston 105 rod 10 divided by the area of the small piston 9 will give the pressure per square inch exerted on the water by piston 9. If the water enters cylinder 19 at 5 pounds pressure per square inch and the area of piston 2 is 40 square inches and the area of piston 9 is 4 square inches then it will be five times 110 40 or 200 lbs. of force on rod 10 dividing the 200 lb. pressure by 4 square inches, the area of the small piston, the pressure of 50 lbs. per square inch will be exerted on the water by the piston 9. It must be borne in mind 115 that the piston 9 is operated in opposite directions so that the water may be forced out through the pipe 99 under a high pressure or through pipe 104 at the same pressure.

120 Since a column of water 1 foot high exerts a pressure of .434 lbs. per square inch, 50 divided by .434 will give 112 feet the height at which the water may be forced in pipe 100, eliminating the element of friction. Now since 5 lbs. of pressure is required to do this 5 divided by .434 will give approximately 11 foot height of water, subtracting 11 feet from 112 feet gives 101 feet which is 125 130

the difference in height the water may be forced. It must be borne in mind that the variations in size of the pistons employed will govern to some extent the height the water will be thrown and the greater the difference between the area of the piston will proportionately increase the height to which the water may be forced. There will also be a proportionate increase in the waste in the water.

The cylinder head 5 is formed of one piece of casting and serves as a cylinder head for both cylinders 1 and 7 and thereby cheapens the cost of production since an air-tight 15 stuffing box forms a unitary structure of the cylinder head. The plugs 42 of the valve boxes 24 and 51 permit the insertion of tools without the necessity of removal of the cover of said boxes for adjusting or grinding the 20 valves.

In Figure 10 the pump is shown connected with a siphon in which the pipe 107 is bent to form a U-shaped conduit having a horizontal portion 108 and a depending portion 109 with the opposite ends of the siphon submerged in water in the tanks 106 and 110. Consider the siphon being employed at sea level where the atmospheric pressure is sufficiently great to support a column of 25 water about 34 feet high, then pipe 107 should be represented as 34 feet and pipe 109 as 44 feet. The water would rise from the surface of the water in tank 106 and stand 109 with the opposite ends of the siphon submerged in water in the tanks 106 and 110. Consider the siphon being employed at sea level where the atmospheric pressure is sufficiently great to support a column of 30 water about 34 feet high, then pipe 107 should be represented as 34 feet and pipe 109 as 44 feet. The water would rise from the surface of the water in tank 106 and stand at A in the pipe 107. It would also rise 35 from the surface of the water in the tank 110 and stand at B in pipe 109. The portion of the pipe 109 between B and the extreme upper end of the pipe would maintain a vacuum when the length of this portion of the pipe is considered as 10 feet. The water standing at A in pipe 107 is 40 passed from A to the top of pipe 109 at zero pressure when pipe 109 is lowered. At the surface of the water in the container 106 the pressure is great enough to support a 45 column of water 34 feet high. Any point taken between the surface of the water in said container and A represents a pressure great enough to support a column of water 50 from the given point to A. The supply pipe 44 is connected at this point in the pipe 107, as shown in Figure 10, at about 10 feet below A in this pipe and the pressure of the water is of such a degree as to support a 55 column of water 10 feet high or a pressure of 4.34 lbs. per square inch. It is obvious that the lower the point of connection of the pipe 44 with the pipe 107, the greater the pressure exerted. The water at 10 lbs. pressure 60 would flow through pipe 44 to the machine and act upon piston 2 for elevating the normal supply of water to a greater height than it is capable of being elevated by the siphon. The horizontal portion 108 of the siphon should not be considered a

part of the structure when the pump 1 is applied to the siphon since it was merely placed in there to illustrate the operation of the siphon and the atmospheric pressure upon water for raising the water at a certain height.

In order to start the machine into operation it will be only necessary to open the spigot to release water from the pipes 100 and when the pressure of the water will act 70 upon the piston 2 in either direction, as has been indicated and depending upon the position of the valves in the valve boxes.

If two sources of water are available and one source is more desirable for use than the other, pipe 94 may be disconnected from pipe 44 and the disconnected end of pipe 94 will be placed in communication with the more desirable source of water and water 75 from this source will be pumped to spigot 101. Pipe 44 will receive its supply for operating the piston 2 from the source which is less desirable. It is to be understood, however, that two separate sources of water may be utilized as explained above 80 when the one source of water is more desirable for delivering the same through the spigot.

What I claim is:

1. The combination with high and low pressure cylinders arranged along a common axis, pistons movable in the cylinders, a piston rod connecting the pistons for simultaneous operation, a siphon connected to the opposite ends of both cylinders for supplying water under pressure to said cylinders, the water pressure in the low pressure cylinder acting on the low pressure piston for operating the high pressure piston and increasing pressure of the water 95 in the high pressure cylinder, and means for reversing the flow of water to the low pressure cylinder, said means comprising inlet and outlet casings, each casing containing a plurality of chambers, with one chamber in communication with the other chamber and valves for controlling the communication between said chambers.

2. The combination with high and low pressure cylinders arranged along a common axis, pistons movable in the cylinders, a piston rod connecting the pistons for simultaneous operation, a siphon connected to the opposite ends of both cylinders for supplying water under pressure to said cylinders, the water pressure in the low pressure cylinder acting on the low pressure piston for operating the high pressure piston and increasing pressure of the water 100 in the high pressure cylinder, means for reversing the flow of water to the low pressure cylinder, said means comprising inlet and outlet casings, each casing containing a 105 plurality of chambers, with one chamber in communication with the other chamber and valves for controlling the communication between said chambers.

110

115

120

125

130

valves for controlling the communication between said chambers, and means for automatically and alternately operating the valves in the casings.

- 5 3. The combination of high and low pressure cylinders arranged along a common axis, pistons movable in the cylinders, a piston rod connecting the pistons for simultaneous operation, a conduit in communication with a source of water located at a lower level than the low pressure cylinder and in communication with the opposite ends of the high and low pressure cylinders, means for controlling the flow of water 10 to the opposite ends of the low pressure cylinder, and a waste pipe connected with the opposite ends of the low pressure cylinder and having its lower end extending into a body of water, said body of water being 15 located at a lower level than the source of water, said controlling means comprising pairs of a plurality of chambers, certain of the chambers being in communication with the other chambers, and valves controlling 20 said communication.

4. The combination with high and low pressure cylinders arranged along a common axis, pistons movable in the cylinders, a piston rod connecting the pistons for simultaneous operation, a siphon connected to the opposite ends of both cylinders for supplying water under pressure to said cylinders, the water pressure in the low pressure cylinder acting on the low pressure piston 30 ton for operating the high pressure piston and increasing pressure of the water in the high pressure cylinder, and means for reversing the flow of water to the low pressure cylinder, discharge pipes connected 35 with the opposite ends of the high pressure cylinder and valves for controlling the flow of water to and from the opposite ends of the high pressure cylinder, a rock shaft carrying the valves and alternately actuating 40 said valve.

5. The combination of a plurality of units comprising high and low pressure cylinders arranged along a common axis and forming pumps for increasing the pressure of the 50 water supplied to the pump, pistons movable in the cylinders, piston rods connecting the pairs of high and low pressure pistons for simultaneous operation, a siphon connected with the opposite end of the low pressure cylinders for supplying water under pressure to said cylinders and also connected 55 with the opposite ends of the high pressure cylinders, the water pressure in the low pressure cylinders acting on their respective pistons for causing operation of the high pressure pistons for increasing the pressure on the water in the high pressure cylinders, and means for automatically reversing the flow of water to the opposite 60 ends of the low pressure cylinders, said 65

means comprising inlet and outlet casings, each casing containing a plurality of chambers, with one chamber in communication with the other chamber and valves for controlling the communication between said 70 chambers.

6. The combination of units of high and low pressure cylinders arranged along a common axis, pistons movable in the pairs of high and low pressure cylinders, a piston rod connecting each pair of pistons for simultaneous operation, a conduit in open communication with a source of water located at a lower level than the pump units and in communication with the opposite ends of the high and low pressure cylinders of the several units, means for controlling the flow of water to the opposite ends of the low pressure cylinders, and a waste pipe connected with the opposite ends of the low pressure cylinders and having its lower end extending into a body of water located at a lower level than the source of water, said controlling means comprising pairs of a plurality of chambers, certain of the chambers 80 being in communication with the other chambers, and valves controlling said communication; a rock shaft carrying the valves for alternately opening and closing the 85 valves.

7. The combination of high and low pressure cylinders arranged along a common axis, pistons movable in the cylinders, a piston rod connecting the pistons for simultaneous operation, an inlet and a discharge valve casing mounted upon diametrically opposite points on the low pressure cylinder, said valve casing being divided into a plurality of chambers, the inlet valve casing being connected with a siphon for supplying one of the chambers with water under pressure, said chamber being in communication with the remaining chambers, valves for alternately controlling the flow of water from the inlet chamber to the other 100 chambers, one of the last mentioned chambers being connected with the forward end of the low pressure cylinder while the remaining chamber is connected with the opposite end of the low pressure cylinder, and means actuated by the moving piston in the low pressure cylinder for alternately operating the valves, the outlet valve casing being 105 divided into chambers, valves controlling communication between one of the chambers and the other chamber.

8. The combination of high and low pressure cylinders arranged along a common axis, pistons movable in the cylinders, a piston rod connecting the pistons for simultaneous operation, an inlet and a discharge valve casing mounted upon diametrically opposite points on the low pressure cylinder, said valve casing being divided into a plurality of chambers, the inlet valve casing 110 115 120 125 130

being connected with a siphon for supplying one of the chambers with water under pressure, said chamber being in communication with the remaining chambers, valves for alternately controlling the flow of water from the inlet chamber to the other chambers, one of the last mentioned chambers being connected with the forward end of the low pressure cylinder while the remaining chamber is connected with the opposite end of the low pressure cylinder, and means actuated by the moving piston in the low pressure cylinder for alternately operating the valves, the outlet valve casing being divided into a pair of inlet chambers and a discharge chamber in communication with the inlet chambers, a pair of valves mounted for alternate cutting off of communication between the inlet chambers and the discharge chamber, means for causing operation of the valves in the inlet casing causing simultaneous operation of the valves in the outlet valve casing.

9. The combination of high and low pressure cylinders, pistons in said cylinders and connected for simultaneous operation, a siphon connected to the opposite end of both of the cylinders for supplying water under pressure to said cylinders, valves for controlling the inlet and outlet of water to the opposite end of the low pressure cylinder, and means for operating the said valves comprising a reciprocating rod connected with the low pressure piston, a shaft mounted for rotation in the low pressure cylinder and provided with a crank, a wheel loosely mounted on the shaft, and means connecting the wheel with the shaft at times for causing a partial rotation of said shaft, means connected with the wheel and the oscillating bar for causing rotation of the wheel in opposite directions, a resilient means connected with the crank for causing positive rotation of the shaft in advance of the rotation of the wheel for causing operation of the inlet and outlet valves.

10. The combination of high and low pressure cylinders arranged along a common axis, pistons movable in the cylinders, a piston rod connecting the pistons for simultaneous operation, an inlet and a discharge valve casing mounted upon diametrically

opposite points on the low pressure cylinder, said valve casing being divided into a plurality of chambers, the inlet valve casing being connected with a siphon for supplying one of the chambers with water under pressure, said chamber being in communication with the remaining chambers, valves for alternately controlling the flow of water from the inlet chamber to the other chambers, one of the last mentioned chambers being connected with the forward end of the low pressure cylinder while the remaining chamber is connected with the opposite end of the low pressure cylinder, means actuated by the moving piston in the low pressure cylinder for alternately operating the valves, the outlet valve casing being divided into chambers, valves controlling communication between one of the chambers and the other chamber, and means for causing operation of the valves in the inlet and outlet casings.

11. The combination of high and low pressure cylinders, pistons movable in the cylinders, a piston rod connecting the pistons for simultaneous operation, an inlet and a discharge valve casing mounted on the low pressure cylinder, said valve casing being divided into a plurality of chambers, the inlet valve casing being connected with a siphon for supplying one of the chambers with water under pressure, said chamber being in communication with the remaining chambers, valves for alternately controlling the flow of water from the inlet chamber to the other chambers, one of the last mentioned chambers being connected with the forward end of the low pressure cylinder while the remaining chamber is connected with the opposite end of the low pressure cylinder, and means for alternately operating the valves, the outlet valve casing being divided into a pair of inlet chambers and a discharge chamber in communication with the inlet chambers, valves mounted for alternate cutting off of communication between the inlet chambers and the discharge chamber, means for causing operation of the valves in the inlet casing causing simultaneous operation of the valves in the outlet valve casing.
